UNITED STATES PATENT OFFICE.

JAMES BRENT CLARKE, OF WASHINGTON, DISTRICT OF COLUMBIA,
ASSIGNOR TO INDUSTRIAL MOTOR COMPANY, A CORPORATION OF
THE DISTRICT OF COLUMBIA.

MARINE AERIAL TRANSPORTATION SYSTEM.

No. 834,871.

Specification of Letters Patent.

Patented Oct. 30, 1906.

Application filed August 27, 1906. Serial No. 332,241.

To all whom it may concern:

Be it known that I, JAMES BRENT CLARKE, a citizen of the United States, residing at Washington, in the District of Columbia, have invented certain new and useful Improvements in Marine Aerial Transportation Systems, of which the following is a specification.

This invention has relation to marine aerial transportation systems; and it consists in the novel construction and arrangement of its parts, as hereinafter shown and described.

The object of the invention is to provide a system of the nature indicated and especially adapted to be used for the purpose of loading and unloading vessels and floating craft of all kinds.

The system may be used to advantage in such places where vessels on account of shoal water, marsh, sand-bars, or other obstructions cannot near the shore.

It may also be used to advantage for loading and unloading where wharf facilities are unavailable.

The system consists, primarily, of a cable trackway which extends from the vessel to the shore and back to the vessel. Such a trackway being of a flexible nature and having a positive terminal and a floating terminal is liable to sag or to become slack. To obviate this difficulty, the vessel is provided with means for automatically taking up any slack that might occur in the cable-trackways. Suitable cars or carriers are adapted to travel upon the said trackway; but as such cars or carriers form no part of this invention they are not illustrated or described in this specification. Current-wires extend parallel with said trackway and are adapted to transmit current to the said cars or carriers for the purpose of propelling the same. The said trackway is mounted upon supports, some of which rest directly upon the bottom of the harbor or upon shoal places traversed by the

trackways. Those track-supports located nearest the vessel are mounted upon floats or pontoons in order that the track in the vicinity of the vessel may rise and fall with the vessel, so as to avoid sharp angles of inclination in the trackway. The track-supports are provided with pivoted rockers of peculiar formation and arrangement. The said track is attached to the rockers in such manner

that the track is retained vertically and laterally by the same, but may move longitudinally. Thus the said rockers do not prevent the slack from being taken up from the track. At the same time the track at the rockers is bowed under the pivotal points of said rockers, and the weight of the track-supports serves in a great measure to prevent the track from becoming slack. Also the said rockers being pivotally mounted will incline or tilt toward an advancing load, and consequently present inclinations thereto, and avoid the formation of precipitous sections in the track at the track-supports. This movement in the rockers will prevent any tendency of the cars or carriers to jump the track in passing over the track-supports.

The terminals of the track, which are located at the vessel and upon the shore, are in the form of superposed trackways suitably supported and carried around in the form of horizontal loops. The said superposed trackways are connected with the main trackway by means of inclined sections which slidably engage rockers mounted upon supports located upon the shore and the vessel. Thus it is possible to adjust the superposed trackways vertically without disconnecting the same from the main trackway. As above indicated, the said superposed trackways are vertically adjustable. Consequently they may be raised or lowered in order that they may be positioned with proper relation to the main trackway irrespective of the condition of the tide—that is to say, that as the vessel rises and falls at the tide the superposed trackway carried by the vessel may be raised or lowered in order that the said superposed trackway may be at the proper elevation with relation to the cable-trackway.

With these and other objects in view, as will appear as the details of the invention are explained, the system embraces the novel arrangement hereinafter pointed out.

In the accompanying drawings, Figure 1 is a perspective view of my system, connecting a vessel with the shore. Fig. 2 is a top plan view of the shore end of the system. Fig. 3 is a side elevation of the shore end of the system. Fig. 4 is a top plan view of the vessel end of the system. Fig. 5 is a side elevation of a portion of the vessel end of the system. Fig. 6 is a detail sectional view of the

rocker used as a connecting means for the main track and the superposed track. Fig. 7 is a sectional view of said rocker disconnected from the superposed track. Fig. 8 is 5 a side elevation of one of the track-supporting poles with parts in section. Fig. 9 is a side elevation of one of the main track-connecting rockers. Fig. 10 is a longitudinal sectional view of the same. Fig. 11 is a side 10 elevation of one of the superposed track-supports. Fig. 12 is a side elevation of the same at right angles to that shown in Fig. 11, and Fig. 13 is a side elevation of a modified form of track-support.

15 This system consists of a series of poles 1, which extend from the vessel 2 to the shore. Some of these poles rest upon the bottom of the harbor or water, while others may be located in marshes or rocks, sand-bars, and 20 shore, and those nearest the vessel are mounted upon pontoons or other buoyant supports 3, the height of the line being adjusted from shore to vessel to suit the contour of land and water by the use of telescopic poles 25 or supports.

25 By referring to Fig. 8 the form of cable-support as used upon a stationary foundation is shown. This support consists of the lower tubular section 4, which is provided at 30 its lower end with a ball 5, which fits into the socket 6. Said socket in turn is provided upon its under side with the pivoted arms 7. The said arms are so hinged that they may swing down when the pole is elevated, but they cannot swing up higher than in a 35 horizontal position when the pole is lowered to the ground. Consequently the said arms prevent the said pole from sinking when placed upon a soft bottom, and the said arms 40 act as lateral braces for the pole. The upper portion 8 telescopes into the tubular portion 4. The said portions 4 and 8 are provided with the registering perforations 9, which are adapted to receive the bolt 10. Thus the 45 portion 8 may be adjusted longitudinally with relation to the tubular portion 4 and secured in such adjusted position. The isosceles frame 11 is mounted upon the upper end of the pole 1. Said frame is provided in 50 its base with a perforation 12, which receives the portion 8 of the pole, and at its apex with the socket 13, which receives the upper end of the portion 8 of the pole 1. The upper ends of the frames 11 are provided with 55 transverse perforations 14, through which the guy-cable 15 passes, the said screw 16 being provided for the purpose of impinging the cable 15 in the perforation 14. The yard-arm 17 is attached directly to the side 60 of the frame 11 at its ends supports the current-wires 18. The rockers 19 are pivotally mounted upon the pins 20, which in turn are screw-threaded into the ends of the frame 11. The friction-roller 21 is journaled 65 upon the pin 20 and the friction-roller 22 is

journaled between the depending flanges 23, carried by the rocker 19. The said rocker 19 is provided with the traction-surface 24. The rocker is provided at points near its ends with the depending flanges 25, between 70 which the friction-rollers 26 are journaled. At their ends the said rockers are provided with the transversely-extending plates 27, which are held in place by means of the taps 28, screwed upon the pins 29. The cable or 75 trackway 30 passes between the traction-surface 24 of the rockers 19 and plates 27 and passes under roller 20 and rests upon the rollers 26. The said track 30 extends from the vessel 2 to the shore. The superposed 80 track 31 is mounted upon the deck of the vessel. Said track 31 is adapted to be adjusted vertically by means of the support 32, which enters the sleeve 33. The parts 32 and 33 are secured together by means of the 85 transversely-extending bolt 34. The rocker 35 is mounted upon a support, which in turn is mounted upon the deck of the vessel 2. The said rocker 35 is of the same general configuration as the rocker 19 heretofore described. The said rocker 35, however, is provided in its traction-surface with the elongated slot 36, through which the inclined section 37 of the superposed track 31 passes. The lower end of the inclined section 37 is 90 pivoted to the sliding member 38, which is supported upon the pins 39, carried by the rocker 35. The upper end of the inclined section 37 is pivotally connected to the superposed track 31. 95

100 From the foregoing description it is obvious that as the track 31 is adjusted vertically the member 38 will slide longitudinally upon the pins 39, and thus the difference in the angle of inclination of the section 37 is 105 compensated for. The superposed track 31 describes a loop upon the deck of the vessel 2. The cable 30 engages the poles and rollers of the rocker 35 and then extends down and winds about the periphery of the drum 40. 110 The said cable 30 then extends to the drum 41, which is alined with the drum 40 and winds about the periphery of the same. The said cable then passes over the edge of the deck and is provided at its ends with pendent 115 weights 42, which may be anchors or any other suitable object. The said cable extends from the vessel 2 to the shore, where it passes around a fixed pulley 43 and extends back to the vessel. Both ends of the cable 120 pass around the drums 40 and 41 at the vessel end of the trackway. Both ends of the superposed track 31 connect with the said cable-track 30, as above described. At the shore end the superposed track 44, in the form of a loop, is provided. The said track 44 is supported upon the poles 45 and is connected with the same by means of the arms 46. Both the superposed tracks at the vessel end and shore end of the trackway are 125 130

made of inflexible bars. The track 44 is connected with the cable 30 by means of inclined sections and the connections similar to that described for section 37 and its immediate attachments. The current-wires 18 extend parallel along the trackway 30. The said trackway 30 is adapted to support any suitable form of carrier, (not shown,) and the current-wires 18 are used for transmitting electric current to the said carriers for the purpose of propelling the same.

By reference to Figs. 11, 12, and 13 of the drawings it will be observed that the arms 46 are provided at their ends with the caps 47, which are screw-threaded upon the upper ends of the supports 45. The said supports 45 also correspond to the supports 32, located upon the vessel 2. The inflexible track is supported at the other end of the arm 46. By means of the screw-thread connection between the cap 47 and the support 45 the arm 46 may be rotated with relation to the support 45 and secured, by means of the brace 48, in such relative position as it may be adjusted to.

The operation of the various parts included in the system are as follows: The floats 3 permit of up-and-down movement of the track 30 near the vessel, and consequently the portion of the track near the vessel will follow the same vertically as the vessel is raised and lowered upon the surface of the water. Consequently sharp angles of inclination in the track in the vicinity of the vessel are avoided. Furthermore, the rockers 19, being pivotally mounted upon their respective supports, sharp angles in the trackway are avoided as the car or carrier (not shown) approaches the said rockers in traveling toward the vessel or toward the shore. As the trackway 30 is provided at its ends with tension weights and is wound around the drums 40 and 41 and extends to the shore, where it passes around the fixed pulley 43, any sag or slack in the said trackway caused by the movement of the vessel is taken up by the said weights and the trackway is at all times kept taut. The peculiar configuration and arrangement of the parts of the rockers 19 afford positive retainers for the said track 30 and at the same time permit of longitudinal movement of the said track in order that slack occurring in the same may be taken up in the manner above described.

It is obvious that one portion of the track 30 is to be used for sending cars to the shore, while the other portion of the said track is to be used for sending cars from the shore to the vessel.

It is also obvious that cargo may be transported either from the vessels at the shore or from the shore to the vessel. Also that the parts may be easily and readily taken down and arranged in compact form for transportation upon the vessel from point to point.

The parts may also be easily and readily erected into operative positions.

As illustrated in Fig. 2 of the drawings, the shore ends of the current-wires 18 are connected together by means of the cross-bar 70, which in turn is attached to the rod 50, said rod being attached at its other end to a ground-anchor 52 and being provided at an intermediate point with a turnbuckle 51. By means of said turnbuckle 51 any slack occurring in the wires 18 may be taken up. However, any other suitable means may be employed for taking up the slack in the current-wires 18.

Having described my invention, what I claim as new, and desire to secure by Letters Patent, is—

1. A system of the character described consisting of an elevated trackway extending from a vessel to the shore and back to the vessel, drums mounted upon the vessel, said track passing around said drums and pendent weights attached to the ends of the track.

2. A system of the character described consisting of an elevated trackway extending from a vessel to the shore and back to the vessel, drums mounted upon the vessel, said track passing around said drums and pendent weights attached to the ends of the track and hanging over the sides of the vessel.

3. A system of the character described consisting of an elevated trackway extending from a vessel to the shore and back to the vessel, alined drums mounted upon the vessel, said track passing around the alined drums and pendent weights attached to the ends of the track.

4. A system of the character described consisting of an elevated trackway extending from a vessel to the shore and back to the vessel, alined drums mounted upon the vessel, said track passing around the alined drums and pendent weights attached to the ends of the track and hanging over the deck of the vessel.

5. A system of the character described consisting of an elevated trackway extending from a vessel to the shore, a superposed rigid track mounted upon the vessel and connecting with the first said trackway, and means for adjusting said superposed track vertically.

6. A system of the character as described consisting of an elevated trackway extending from a vessel to the shore and back to the vessel, a superposed rigid track mounted upon the vessel and connected with the first said track, and means for adjusting said superposed track vertically.

7. A system of the character described consisting of an elevated trackway extending from a vessel to the shore, a tension-weight attached directly to the track and pendently suspended upon the vessel.

8. A system of the character described

consisting of an elevated track extending from a vessel to the shore and back to the vessel, tension-weights attached directly to the ends of the trackway, and pendently suspended upon the vessel.

9. A system of the character described consisting of an elevated track extending from a vessel to the shore, a superposed rigid track mounted upon the vessel, a rocker mounted upon the vessel and connecting the superposed track with the first said track.

10. A system of the character described consisting of an elevated track extending from a vessel to the shore and back to the vessel, a superposed track mounted upon the vessel, rockers mounted upon the vessel and connecting the superposed track with the first said track.

11. A system of the character described consisting of an elevated track extending from a vessel to the shore, a superposed track mounted upon the vessel, a rocker mounted upon the vessel and connecting with the first said track, said superposed track having sliding connection with said rocker.

12. A system of the character described consisting of an elevated track extending from a vessel to the shore, a superposed track mounted upon the vessel, means for adjusting said superposed track vertically, a rocker mounted upon the vessel and being connected with the first said track, said superposed track having sliding connection with said rocker.

13. A system of the character described consisting of an elevated track extending from a vessel to the shore and back to the vessel, a superposed track mounted upon the vessel, rockers mounted upon the vessel and connecting with the first said track, said superposed track having at its ends sliding connection with said rockers.

14. A system of the character described consisting of an elevated track extending from a vessel to the shore and back to the vessel, a superposed track mounted upon the vessel, means for adjusting said superposed track vertically, rockers mounted upon the vessel and connecting with the first said track, said superposed track having at its ends sliding connection with said rockers.

15. A system of the character described consisting of an elevated track extending from a vessel to the shore, a track mounted upon the vessel, a rocker mounted upon the vessel and connecting the terminals of said tracks together.

16. A system of the character described consisting of an elevated track extending from a vessel to the shore, a vertically-adjustable track mounted upon the vessel, a rocker mounted upon the vessel and connecting the terminals of said tracks together.

17. A system of the character described consisting of an elevated track extending

from a vessel to the shore, a track mounted upon the vessel, a rocker mounted upon the vessel and having sliding connection with both said tracks.

18. A system of the character described consisting of an elevated track extending from a vessel to the shore superposed tracks located at the shore and upon the vessel, rockers located upon the vessel and upon the shore and connecting the terminals of the said track together.

19. A system of the character described consisting of an elevated track extending from a vessel to the shore, superposed tracks located at the shore and upon the vessel, rockers located upon the vessel and upon the shore and slidably connecting the ends of the said tracks together.

20. In a system of the character described, a flexible track, track-supports, rockers pivoted upon said supports, said rockers passing over the track and having traction-surfaces.

21. In a system of the character described, a flexible track, track-supports, rockers pivoted upon said supports, said flexible track bowing under the rocker-pivots, said rockers having traction-surfaces.

22. In a system of the character described, a flexible track, track-supports, rockers pivoted upon said supports, said rockers extending over the track and having traction-surfaces, said track bowing under the intermediate portions of said rockers.

23. In a system of the character described, an elevated track, poles for supporting the same, isosceles frames having at their bases perforations which receive the poles, and at their apexes sockets which receive the upper ends of the poles, and means located at the ends of the said frames for attachment with the said track.

24. In a system of the character described, an elevated track, poles for supporting the same, isosceles frames having at their bases perforations which receive the poles, and at their apexes sockets which receive the upper ends of the poles, means located at the ends of the frame for attachment with the said track, and a wire-supporting yard-arm attached to said frame.

25. In a system of the character described, an elevated track, poles for supporting the same, isosceles frames having at their bases perforations which receive the poles, and at their apexes sockets which receive the upper ends of the poles, and rockers pivoted to said frame and engaging the track.

26. A system of the character described comprising an elevated flexible track connecting a vessel with the shore, and a plurality of track-supports extending from the vessel to the shore and each provided with means for applying tension to said track.

27. A system of the character described comprising an elevated flexible track con-

necting a vessel with the shore, track-supports resting upon solid foundations and sustaining the track from a point near the vessel to the shore, and track-supports resting upon floating foundations near the vessel, said track-supports being each provided with means for applying tension to said track.

28. A system of the character described comprising an elevated trackway connecting a vessel with the shore, track-supports located in or upon the water and extending from the vessel to the shore, and means mounted on each track-support for applying tension to said track.

29. A system of the character described consisting of track-supports extending from a vessel to the shore, an elevated track suspended from said supports, and means carried by each support for applying tension to said track, said tension means permitting longitudinal movement of said track.

30. A system of the character described comprising track-supports extending from a vessel to the shore, an elevated track suspended from said supports, and tension devices for said track pivotally mounted on each support.

31. A system of the character described comprising track-supports extending from a vessel to the shore, an elevated track suspended from said supports, and tension devices secured to each track-support and provided with traction-surfaces.

32. A system of the character described comprising track-supports extending from a vessel to the shore, tension devices carried by each track-support, and an elevated track suspended from said tension devices.

33. A system of the character described comprising track-supports extending from a vessel to the shore, tension devices mounted on said track-supports, and an elevated track loosely suspended from said tension devices,

whereby longitudinal movement of the track is permitted.

45

34. A system of the character described comprising an elevated track extending from a vessel to the shore, a superposed track on the vessel having a sliding engagement with said elevated track, and a traction-surface bridging said sliding connection.

35. A system of the character described comprising an elevated track extending from a vessel to the shore, a superposed track on the vessel having a sliding engagement with said elevated track, and a tension device for said elevated track and bridging said sliding connection.

36. A system of the character described comprising an elevated flexible track extending from a vessel to the shore, a superposed track on the vessel joining said elevated track, and a tension device for said flexible track bridging the point of union of said tracks.

37. A system of the character described comprising an elevated flexible track extending from a vessel to the shore, a superposed track on the vessel joining said elevated track, means for adjusting said superposed track vertically, and a tension device for said flexible track bridging the point of union of said tracks.

38. A system of the character described comprising an elevated track, track-supports, floating bases for said track-supports, and tension devices for said track carried by said track-supports.

In testimony whereof I have signed my name to this specification in the presence of two subscribing witnesses.

JAMES BRENT CLARKE.
